UNITED STATES PATENT OFFICE.

WILLIAM JAEGER, OF PHILADELPHIA, PENNSYLVANIA, ASSIGNOR TO HENRY M. KOFSKY, OF PHILADELPHIA, PENNSYLVANIA.

DESIGN FOR A CEILING-TYPE LIGHTING FIXTURE.

Application filed October 11, 1924. Serial No. 11,037. Term of patent 7 years.

To all whom it may concern:

Be it known that I, WILLIAM JAEGER, a citizen of the United States, residing at Philadelphia, in the county of Philadelphia and State of Pennsylvania, have invented a new, original, and ornamental Design for Ceiling-Type Lighting Fixtures, of which the following is a specification, reference being had to the accompanying drawings, forming part thereof.

Fig. I is a side elevation, and
Fig. II a plan view showing my improved
design.

I claim:
The ornamental design for a ceiling type
lighting fixture, as shown.

WILLIAM JAEGER.
